STEAM AND DRY FLATIRON
Bryce A. Denton, Ontario, Calif., assignor to General
Electric Company, a corporation of New York
Continuation of application Ser. No. 78,942, Dec. 28,
1960. This application June 17, 1963, Ser. No. 290,273
2 Claims. (Cl. 38—77)

This invention relates to electrically heated flatirons of the type adapted to be operated selectively as a dry iron or as a steam iron, and in which liquid may be converted to vapor more or less instantaneously upon deposit of liquid into a heated steam generating cavity in regulated small quantities.

This application is a continuation of my application Serial Number 78,942, filed December 28, 1960, now abandoned, and assigned to General Electric Co., assignee of this application.

Effective ironing of a fabric requires application of a smoothing device such as the soleplate of a flatiron, heated to the proper temperature, applied with a given pressure through a duration of the proper short interval of time. Thus, temperature, pressure or touch, and time are the principal variables. In most cases with modern electric flatirons, the ironing pressure is controlled predominantly by the weight of the iron itself and the area of the flatiron soleplate. The interval of time of application is primarily a function of the speed with which the operator moves the iron over the fabric. This factor, while varying from user to user, must be accepted by the manufacturer of flatirons on the basis of a fixed, though possibly estimated average. Correspondingly, the only real variable with respect to a modern automatic electrically heated flatiron is the temperature at which the ironing or smoothing surface is operated. For example, the more delicate synthetic fiber fabrics, such as acetates or fabrics made with the trademarked fibers called Dynel, may require temperatures as low as 220° F. Rayon, nylon, and fabrics made from synthetic fibers such as those sold under the trade name "Dacron," can stand temperatures in the range of 275° F. to 300° F.; while wool, cotton, and linen typically are described as requiring ironing temperatures of 340° F., 405° F., and 455° F., respectively.

The typical well-known shape for a flatiron soleplate provides a pointed toe end and a broad heel end, such shape having been found satisfactory by the typical user. In modern practice, the flatiron soleplate is heated by an electric heating element, preferably of the sheathed form. The most efficient heat transfer occurs when such a heating element is cast integrally into a soleplate made of aluminum, an aluminum alloy, or other suitable highly heat conductive metal. The modern tendency also is to provide a lightweight low-mass soleplate which heats very rapidly. For satisfactory operation with such a soleplate having, for example, thirty square inches of ironing surface, it has been found that the heating element should provide a capacity in the order of 1100 watts. Since the total length of the heating element usable may only be twelve or thirteen inches, it is necessary to provide such a sheathed heating element having a high output per unit length. For this reason, the electrical wire embedded within the tubular sheath is coiled, for example in the form of a helix.

It is well known in flatiron practice that the helix or coil of the heating element may be stretched or compressed to reduce or increase, respectively, the heat output of the element per unit length. Thus, in accordance with one construction used widely and successfully, the helix of the heating element has been stretched at the bight or nexus of the element as located adjacent the pointed end of the iron. Such a construction reduces the wattage of heat applied to the reduced area at the pointed end of the

iron. Such a construction is shown, for example, in Finlayson Patent 2,582,773, issued January 15, 1952, and assigned to the General Electric Company, assignee of the instant application. The express purpose of such a construction as shown by the patent, is to provide a uniform temperature over the entire soleplate when the iron is used as a dry iron, with no steam generation.

Other configurations of the heating element coil have been used for optimum performance in connection with steam iron operation. The typical approach in this instance is to provide concentrated heat adjacent the flash steam generator so that this area of the heated soleplate will always be over a minimum temperature in the order of 230° F. It has been found from experience that maintenance of a temperature lower than 230° F. tends to result in occasional flooding of the flash steam generating cavity, such as when an excessive quantity of water suddenly flows onto this area. Flooding is a most unsatisfactory operating condition, for the reason that discrete drops of water are suddenly expelled through the soleplate, possibly staining or damaging the fabric being ironed.

Flooding of the steam generator cavity has proved to be a particularly troublesome problem in connection with modern irons designed for ironing the delicate synthetics. As explained above, when the synthetic fabrics are ironed, a relatively low temperature setting or adjustment is selected for the flatiron thermostatic switch. Under these circumstances, the steam generating cavity tends also to operate at a lower temperature, and possibly at such a low temperature that flooding will result if liquid is allowed to flow into the steam generating cavity at a rate to provide sufficient steam for satisfactory steam ironing.

In the past, the design of flatiron soleplates, including the heating element configuration and thermostat mounting, have been selected on the basis of steady state operating conditions. For example, a flatiron is allowed to come up to temperature, followed by several on-off cycles of the thermostatically controlled switch. Measurements of soleplate temperatures are thereupon taken at several locations, and the concentration of the heating element is adjusted as necessary to provide a substantially uniform temperature over the entire soleplate. However, this approach to flatiron construction overlooks the serious problems which may be created by transient temperature variation conditions at different points on a flatiron soleplate. For example, when an iron has been operating for a period of time as a dry iron and is then switched to steam iron operation, there is a sudden drop in temperature in the steam generating cavity, caused by the evaporation of liquid and the cooling of this area by the liquid. If the temperature drops too rapidly, the cavity is flooded as described above. Therefore, sufficient heat must be supplied to this cavity to maintain it at the proper operating temperature; however, when this is done, an excessive rise in temperature adjacent the heel of the iron likely will occur.

Most of the steam irons which employ an instantaneous or flash steam generator are arranged to cease steaming automatically whenever the iron is up-ended onto its heel rest. In other words, when the iron is up-ended onto its heel rest, liquid ceases flowing to the steam generator. However, the change in operating condition is not immediately sensed by the temperature responsive member which operates the thermostatic switch. Therefore, as a transient condition, certain portions of the flatiron soleplate tend to overheat until the iron again reaches a steady state condition. If the operator should decide to again apply the iron with a portion of the soleplate in such an overheated condition, there is appreciable risk of damage, particularly when ironing a delicate fabric such as one of the synthetics.

Correspondingly, one of the objects of this invention

is to provide a flatiron operable selectively as a dry iron or a steam iron with an electric heating element and an automatic temperature control, so arranged to minimize abnormal transient temperature conditions.

A further object of this invention is to provide a flatiron capable of operation for steam ironing delicate synthetic fabrics, without risk of scorching or melting the fibers from which the fabric is made.

Still another object of this invention is to provide an iron with an automatic adjustable temperature control, operable for steam or dry ironing, and providing a more uniform heat over the surface of the soleplate under all operating and transient conditions, and in all temperature ranges.

A further object is to provide such an all-purpose flatiron, useful for dry ironing, steam ironing, and any other ironing tasks, at a minimum manufacturing cost, and which maintains reliably uniform operating temperatures over the surface of the soleplate under all steady state as well as transient conditions.

Briefly stated, in accordance with one aspect of this invention, a combination steam and dry iron includes a cast-in elongated sheathed electrical heater, U-shaped to conform generally with the configuration of the soleplate with the nexus or bight of the heating element adjacent the pointed end of the iron and legs of the heating element extending adjacent the side edges rearwardly toward the heel of the soleplate. The soleplate has a nose portion and a heel portion of comparable areas measured at the smoothing or ironing surface. The steam generating cavity is located within the nose portion of the soleplate, and the temperature sensing element of the thermostatic switch assembly is mounted adjacent the steam generating cavity, to respond as quickly as possible to changes in temperature when liquid is introduced into the cavity. The heating element itself is constructed to emanate less heat per unit length in the legs thereof, which are positioned in the heel portion of the soleplate, compared to the heat concentration emitted per unit length along the heater at the nose portion of the iron. This construction materially reduces the transient temperature overshoots at various critical points of the ironing surface.

The subject matter which I regard as my invention is particularly pointed out and distinctly claimed in the concluding portion of this specification. My invention, however, both as to organization and method of operation, together with further objects and advantages thereof, may best be understood by reference to the following description taken in connection with the accompanying drawings in which:

FIG. 1 is a side elevation, with certain surfaces broken away and partially in section, of a steam and dry iron in accordance with the present invention; and

FIG. 2 is a plan view, with certain surfaces broken away and partially in section, of a soleplate assembly in accordance with the present invention.

Referring now to the drawings, in FIG. 1 is shown a typical flatiron of the type to which this invention may be applied, comprising a smoothing member or soleplate 1, a cover 2 enclosing various components within the iron, and an operating handle 3 molded from a thermal insulating material. Electric power may be supplied to the iron through a conventional cord (not shown) which enters the iron through the handle by means of a cord lift bushing 4. In order to adapt the iron for application to various fabrics, a temperature selector 5 is provided adjacent the top forward portion of handle 3 for convenience of the operator in selecting the desired operating temperature. Also, the iron is provided with a push button 6 or the equivalent which can be operated, for example, by an up-and-down motion, to convert the iron from dry to steam operation or vice versa in a manner to be described.

Thermostatic switches for controlling operating temperature of a flatiron are, of course, well known in the art. In this particular embodiment, the temperature

responsive element is in the form of a bimetallic blade 7 firmly secured to the flatiron soleplate 1 by means of a bolt 8. Such bimetallic blades, in a well known manner, exhibit the characteristic of deforming or bending responsive to heat. In this particular instance, blade 7 is mounted so that it will bend or deform downwardly responsive to increasing temperature of the soleplate. Adjacent the outer end of the bimetallic blade 7 is a second bimetallic blade 9 of shorter length for temperature compensation purposes. This short bimetallic blade 9 is oriented to deflect upwardly responsive to increasing temperature. In accordance with well-established practice, this compensating blade evens out the variations in temperature while the iron is coming up to steady state operating conditions. Motion of this compound bimetallic blade assembly is transmitted to the electrical switch arm, presently to be described, by means of a U-shaped bracket 10 secured to the outer end of compensating bimetallic blade 9. Bracket 10, in turn, may include an adjusting screw 11 usable for factory calibration of the thermostatic switch assembly.

In accordance with this embodiment, the electrical switch itself is made up of a first arm 12 of resilient material, secured as by rivets 13 and 14 (FIG. 2) to an electrical insulating block 15. The end of resilient arm 12 adjacent the heel end of the iron includes a terminal screw 16 to which one of the ~~the~~ ^{incorrect} electrical conductors may be secured. The opposite end of this resilient arm 12 is secured to a rigid or substantially rigid contact arm 17, with a suitable electrical insulating member 18 encompassing the corresponding ends of both resilient arm 12 and contact arm 17. Contact arm 17, in turn, extends rearwardly and includes on its opposite free end an electrical contact 19 adapted to cooperate with a fixed contact 20 mounted on the end of a substantially rigid terminal strip 21. Conveniently, the rigid contact arm 21 may also be mounted to insulator block 15, for example by rivets 22 and 23. This insulator block 15 is shown in FIG. 2 as secured to a rigid frame 24 adapted to be bolted or otherwise secured to the soleplate by suitable fastening devices 25 and 26. By this means, the insulator 18, on the ends of the movable contact arm and the resilient arm, is positioned to overlie a temperature selection cam 27. This cam has an appropriately sloped top surface, which upon rotation thereof adjusts the position of contact arm 17 with respect to the insulating tip 28 which projects from calibration screw 11 carried by the bracket 10 of the temperature responsive member. Cam 27, for temperature selection, is rotatable by a shaft or other suitable connecting device 29, which shaft extends upwardly through the body of the iron and the front handle support for adjustment or rotation by the temperature selector knob 5. This temperature adjustment control mechanism is, of course, appropriately calibrated so that selector knob 5 may be moved from an "off" position to successive positions to adjust the thermostatic switch assembly to maintain progressively higher temperatures of the soleplate up to the highest operating temperature. In accordance with usual practice, a dial plate 30 cooperable with knob 5 may be calibrated with the names of different types of fabrics, commencing at the low temperature end with designations of various synthetics and continuing through rayon, wool, and cotton, up to linen at the high temperature end of the scale.

The present invention is of particular importance with respect to its application to a combination steam and dry iron in which steam is generated in a so-called flash steam generator. A typical form of such a steam generating system is illustrated in FIG. 1 and includes a liquid reservoir 31 enclosed within cover 2. This reservoir may be supported in any suitable manner within the iron, and typically is supported at its forward end by a steam dome 32, preferably made of stainless steel to reduce heat transfer to the liquid carried within reservoir 31. Steam dome 32 forms a part of a boiler cover plate 33 secured to soleplate 1 and

overlying and enclosing a steam generating cavity 34 formed in the soleplate. To provide communication between the liquid reservoir and the steam generating chamber, an orifice member 35 is employed with a restricted passageway 36 through which liquid may flow at a slow rate, such as drop by drop. Cooperating with orifice member 35 is a valve stem 37 arranged suitably to be operated by steam control push button 6. Valve stem 37 is normally biased in an upwardly direction by a compression spring 38, so that liquid may flow through the restricted orifice 36 into the steam generating cavity. A clean-out pin 39 is provided on the end of the valve stem to project through orifice 36 when push button 6 is depressed to terminate or shut off liquid flow from the reservoir into the steam generator. This liquid supply and steam generating system may also include a pressure balancing tube 40 to equalize the pressure between the steam generating cavity and the upper portion of reservoir 31. Also, appropriate means is provided for filling the reservoir with liquid, typically in the form of a funnel member 41 in the forward portion of the front handle support communicating with the interior of the reservoir. For further details with respect to this liquid supply and steam generating system, reference is made to Patent No. 2,892,272, issued June 30, 1959, and assigned to the General Electric Company, assignee of the present invention.

The heating means for the flatiron soleplate and for the steam generating cavity is in the form, preferably, of a sheathed tubular heater. Such a heater may be cast integrally into soleplate 1, and it has been found that aluminum or an aluminum alloy is particularly suitable for the soleplate casting, in that such a metal is highly conductive of heat. The heating element itself comprises a coiled resistance wire 42, formed typically in a helix. This resistance wire is held in spaced relation within an outer protective sheath 43 by a mass of highly compacted electrical insulating material 44, such as granulated magnesium oxide. At each end of the heater, the resistance wire is connected in any appropriate fashion to respective terminal pins 45 and 46. As shown in FIG. 2, terminal pin 46 is connected to a terminal lug 47 for one of the conductors of the electrical power supply. The other terminal pin 45 is connected through a conductor 48 to contact strip 21. Thus, when the thermostatic switch is closed, electrical power can flow through the resistance wire, the thermostatic switch, and back to terminal 16, to which is connected the other side of the line of the power supply.

In accordance with modern practice, the entire iron, and especially the soleplate, is made as lightweight as is feasible. It has been found in practice that such a lightweight iron is just as effective as heavier irons for smoothing fabrics, and can be operated with considerably less fatigue. However, since a lightweight iron provides very little heat storage, it is necessary to provide a high electrical power input to heat the soleplate quickly, and thus make up for heat lost in operation. The heating element in this application is, for example, in the neighborhood of 1100 watts. Obviously, it is desirable for the thermostat and heating element to be arranged to maintain the pre-selected temperature for the soleplate. This consideration alone would tend to indicate that the temperature-sensitive blade should be mounted at the geometric center of the soleplate. However, an iron in accordance with the present invention includes also the steam generating cavity into which liquid is deposited for conversion into steam. As liquid is deposited into this cavity, the soleplate in the area is quickly cooled. It has been found in practice that if the metal in the immediate vicinity of the steam generating cavity drops to a temperature below 230° F., there is substantial risk that the steam generating cavity will flood and discharge droplets of liquid through the soleplate onto the fabric being ironed. Correspondingly, in accordance with this invention, I prefer to mount the thermostat temperature sensing element in close proximity to the steam generating cavity.

As shown, the steam generating cavity is located in the forward portion of soleplate 1. The reason for this is that an iron should cease steam generation whenever it is upended onto its heel rest. This is accomplished conveniently by arranging the steam generator and the orifice member 35 forwardly in the iron, so that whenever the iron is upended to its rest position, orifice 36 will be above the water level. Correspondingly, the soleplate, in accordance with this invention, may be described as consisting of a forward portion, above line A—A of FIG. 2, and a heel portion below the line. The forward portion includes steam generating cavity 34 as previously described. The iron of this invention is provided with a heating element of sufficient wattage for the heaviest ironing load expected. For example, one of the heaviest loads would be presented when smoothing a heavy cotton or linen fabric that had been damped to a substantial extent. Under these circumstances, or under the condition when the iron is initially heating up, it is conceivable that the thermostatic switch would remain closed for an appreciable period of time. However, for most ironing operations, the thermostatic switch cycles between "on" and "off" conditions rather frequently to maintain the pre-selected temperature.

For dry ironing alone, it might be reasoned that the electric heating element should provide a substantially uniform wattage output per square inch of soleplate area. For example, such a wattage in a modern iron might be in the range of 35 to 40 watts per square inch of soleplate area. Such considerations might also suggest that the heating element should be stretched or arranged to provide less watts per unit length at the nose or pointed end of the iron, in view of the fact that the area to be heated at the nose of the iron per unit length of heating element is correspondingly less than such area per unit length of heating element at the heel portion of the iron. Such a construction is, in fact, disclosed and claimed in Patent 2,582,773, Finlayson, issued January 15, 1952, and assigned to the General Electric Company, assignee of this invention. Other arrangements have been heretofore proposed for varying the heat dissipation per unit length of the heating element in order to achieve a desired heat distribution pattern.

The present invention is directed particularly to a steam and dry iron suitable for use in the relatively low and narrow temperature ranges required for smoothing the various synthetic fabrics. For this application, the normal steady state heat distribution patterns become of less importance than the temperature variations at various points on the soleplate arising out of transient conditions. For example, one serious transient condition may occur after the iron has been operating as a dry iron for a sufficient length of time for the thermostatic switch to arrive at its normal cycle of operations between "on" and "off" conditions, thus maintaining the preselected temperature. Then, when the liquid supply orifice is opened and water is deposited into the steam generating cavity, this portion of the soleplate is suddenly chilled. As soon as this change in temperature is sensed by the bimetallic element or heat sensing member, the thermostatic switch is closed, and remains closed for a sufficient period of time to again heat the steam generating cavity up to the desired extent. However, during this time when the thermostatic switch is closed, serious overheat conditions may exist temporarily or transiently at some other point on the flatiron soleplate, such as the area of the soleplate adjacent the heel.

In order to minimize wide temperature variations over the soleplate under such transient conditions, it has been found that the soleplate may be considered as including a nose portion with a steam generating cavity therein and a heel portion, these two portions being of generally comparable areas. In one typical example, the nose portion of the soleplate presented an area of approximately 15 square inches, while the heel portion of the soleplate in-

7
volved essentially the same area, with a total soleplate area of approximately 30 square inches. In contrast to prior constructions, the heating element, here shown in the form of a helix, is relatively concentrated throughout its length in the nose portion of the iron, while the helix is stretched to reduce the watts output per unit length for the lengths or legs of the heating element in the heel portion of the soleplate. In a typical example, a concentration of 110 watts per inch has been used for the heating element length in the nose portion of the soleplate, to provide approximately 60 watts per square inch of soleplate area over the nose portion of the soleplate. However, for the legs of the heating element in the heel portion of the soleplate, it has been found that 48 watts per inch helps materially in reduction of transient temperature conditions which might lead to damage of delicate fabrics. With 48 watts per inch of heating element in the heel portion, the watts per unit of area of the soleplate is reduced to a value of 12 to 14 watts per square inch.

To avoid danger of flooding in the steam generating cavity, it is preferred to mount the temperature sensitive element 7 of the thermostatic switch assembly immediately adjacent to the steam generator. With such an arrangement, there is a minimum delay between the initial chilling of the steam generating cavity when water is admitted thereto and the time when such reduced temperature is sensed by the bimetallic blade. In other words, the temperature sensing element responds very quickly to energize the heating element whenever liquid is introduced into the steam generating cavity.

With the construction in accordance with this invention as described above with the heating element helix stretched in the heel portions of the flatiron soleplate, one of the most serious transient overtemperature conditions is materially improved. For example, in accordance with prior flatiron constructions, temperature rises of 170° F. above normal have been noted directly under the heating element in the heel portion of the iron upon introduction of liquid in the steam generating cavity. In accordance with the present invention, this temperature overshoot has been reduced by a magnitude in the order of 40° F. in the specific example described above. At the same time, the mounting of the temperature sensing element of the thermostatic switch assembly immediately adjacent the steam generating cavity has resulted in a significant increase in the lowest temperature found to exist in the cavity area upon initiation of steam generation. This is also a very definite improvement in the sense that the risk of a flooding condition is obviated, even for relatively low settings of the thermostatic switch. Therefore, it is now possible with an iron in accordance with the present invention to steam delicate fabrics; while the material reduction in the transient temperature overshoot in the heel portion of the iron materially reduces the risk of damage or scorching of such delicate fabrics.

While the present invention has been described by reference to particular embodiments thereof, it is to be understood that numerous modifications may be made by those skilled in the art without actually departing from the invention. It is, therefore, the aim of the appended claims to cover all such equivalent variations as come within the true spirit and scope of the foregoing disclosure.

I claim:

1. A steam and dry iron soleplate of high heat conductivity metal comprising a nose portion including a steam generating cavity into which liquid may be deposited for substantially instantaneous conversion into steam, a heel portion, said heel and nose portions being of generally comparable areas, a single elongated heating element for both steam and dry ironing extending integrally within the soleplate and following the external contour thereof, a thermostatic switch mechanism controlling power input to said heating element including a heat sensing member mounted centrally on said soleplate at a portion thereof which defines a wall of said steam generating cavity to sense predominantly the temperature of said steam generating cavity and secondarily the temperature of said heel portion, said heating element being constructed to provide greater heat output per unit length in the nose portion so that the total heat generated in that portion of the heating element in the nose portion of the soleplate exceeds by a factor in the order of four or five to one the heat output of the portions of the heating element in the heel portion of the soleplate.
2. A combined steam and dry iron soleplate cast of a high heat conductivity metal comprising a nose portion and a heel portion, said nose portion being a substantial portion of said soleplate and extending from the tip of said soleplate rearwardly more than half of the center line dimension of said iron, said heel portion comprising the remaining portion of said soleplate, a steam generating cavity integrally cast in the nose portion of said iron, an upwardly extending wall integrally cast in the nose portion of said soleplate, the forward surface of said wall providing the rear inner surface of said steam generating cavity, a single cast-in sheathed heating element in said soleplate generally following the external contour of said soleplate inwardly thereof for providing heat for both steam and dry ironing, said heating element being concentrated throughout its length in the nose portion of said iron and being stretched in the heel portion of said soleplate so that the total heat generated in the portion of the heating element in the nose portion of the soleplate exceeds by a factor of approximately four to one the heat output of the portions of the heating element in the heel portion of the soleplate, a thermostatic switch mechanism for controlling power input to said heating element, said switch mechanism including a heat sensing member mounted on said steam generating cavity wall and extending rearwardly to a position above the heel portion of said soleplate to sense both the temperature of said steam generating cavity and the temperature of the heel portion of said soleplate, whereby said iron may be effectively used for both steam and dry ironing with a minimum transient temperature overshoot in said heel portion upon change from dry to steam ironing.
